UNITED STATES PATENT OFFICE.

GEORGE W. STOCKMAN, OF INDIANAPOLIS, INDIANA.

ABSORBER FOR AMMONIA-REFRIGERATORS.

SPECIFICATION forming part of Letters Patent No. 275,869, dated April 17, 1883.

Application filed November 22, 1882. (No model.)

To all whom it may concern:

Be it known that I, GEORGE W. STOCKMAN, of Indianapolis, Indiana, have invented a new and useful Improvement in Absorbers for Ammonia-Refrigerators, of which the following is a description, reference being made to the accompanying drawings, in the several figures of which like letters indicate like parts.

My invention is designed to supply an absorber for ammonia-refrigerating apparatus which, by its peculiar construction, shall bring the weak liquor in contact with a large extent of surface cooled by the vapor from the refrigerator, and thus prevent heat, and to allow the weak liquor and vapor to unite after the liquor has been cooled and at or near the place of outlet, where it is taken up by the suction of the pump.

In the drawings, Figure 1 is a vertical section 20 of my absorber; and Fig. 2 is a cross-section of the shell and a top view on the line *xx*, Fig. 1.

In detail, *a* is the shell of the absorber, which must be of material strong enough to resist considerable pressure, in either end of which 25 are riveted heads *h h'*.

V is the pipe which conducts the ammonia vapor from the refrigerating-coil after it has done its work into the absorber.

ff' are flue-sheets, in which are welded tubes 30 *t t t*, (shown more fully in Fig. 2,) similar to those in a tubular boiler. *o* is the opening or chamber between the upper head and flue-sheet.

A short distance below the upper flue-sheet, *f*, is a percolator-plate, *p*, also secured to the 35 sides of the absorber-shell, having openings of greater diameter than the tubes, through which openings the tubes pass.

W is a pipe through which the weak liquor is received into the absorber. It falls upon 40 the percolator-plate *p*, and escapes through the openings around the tubes, and, trickling, falls downward, following the tubes, until it reaches the bottom flue-sheet, *f'*, where it stops and accumulates until it is mixed with the gas

45 and is carried away by the pump through the outlet-pipe *P*. Thus the weak liquor is contained in the chamber between the two flue-sheets and around the tubes.

g is a glass gage for showing the height of 50 the water or weak liquor. The vapor or gas

comes from the refrigerating-coil through the pipe *V*, and is allowed to break its force and be distributed from the shield *S*, and then passes down through the tubes *t t t* into the opening *o'*, between the flue-sheet *f'* and bottom head, *h'*, and from this chamber it escapes through the bend and check-valve *C v*, which is kept open so long as there is pressure, and closes when the machine is not in operation, and the gas thus mingles with the weak liquor, 55 which, cooled in its passage down the tubes, absorbs the gas readily, and the liquor becomes strong and rich, and it is now drawn out the pipe *P* by the suction of the pump and thrown again into the retort, to be again vaporized, as shown in my Letters Patent No. 245,325, dated August 9, 1881, and No. 264,113, dated September 12, 1882. The union of the vapor and weak liquid is secured at a point close to the suction-pipe of the pump, so that it is drawn 60 off and away from the absorber immediately, and the heating of the absorber is prevented and the heat carried away into the retort with the liquid.

What I claim, and desire to secure by Letters 75 Patent, is—

1. An absorber for ammonia-refrigerators in which upper and lower gas-chambers are formed in the interior between the ends of the absorber and flue-sheets, in which tubes are 80 welded for conducting the gas from the upper to the lower gas-chamber, and provided with a percolator placed below the upper flue-sheet, having openings to permit the passage of water downward and around the tubes, with a 85 connection between the lower gas-chamber and the space above the lower flue-sheet for the admission of the vapor, so that it will unite with the weak liquor, with an inlet for receiving the weak liquor into the space between the 90 upper flue-sheet and the percolator-plate, and an outlet for discharging the enriched liquor in close proximity to a pump, substantially as described.

2. An absorber for ammonia-refrigerators 95 wherein the weak liquor is cooled by contact with the outer surfaces of a series of tubes, through which the cold gas from the refrigerating coil or chamber is conducted, with means for uniting the weak liquor and gas after its 100

passage through these tubes in close proximity to the suction-pipe of a pump, substantially as described.

3. An absorber for ammonia-refrigerators having upper and lower gas-chambers, o o' , upper and lower flue-sheets, f f' , with tubes welded therein t t t , a distributing-shield, S, under the receiving vapor-pipe V, a percolator-plate, p, below the upper flue-sheet, a weak-
liquor inlet-pipe, W, a check-valve connection,

C v, between the lower gas-chamber, o' , and the weak-liquor chamber, and an outlet-pipe in close proximity to a pump, substantially as described.

Witness my hand this 18th day of November, 1882.

GEO. W. STOCKMAN.
